COMBINED MACHINE FOR FEEDING, BENDING, AND FLATTENING TUBING

James R. Hayward, Washington, and John A. Schild and William O. Hartup, Columbus, Ind., assignors, by mesne assignments, to McCord Corporation, Detroit, Mich., a corporation of Maine

Application June 28, 1946, Serial No. 680,124

13 Claims. (Cl. 153—2)

1
This invention relates to a tube bending and flattening machine.

Serpentine coils for heat exchangers such as condensers are now commonly made of round tubing which is bent to form spaced, parallel runs and the runs of which are flattened and have fins attached thereto. The patent to Mc-Intyre 1,789,591, issued January 20, 1931, for "Heat exchange apparatus" discloses an early form of condenser of this type. The bending and flattening of such tubing, as heretofore practiced, involves considerable labor, costs and/or relatively great investment in dies for the flattening operations. The present invention contemplates a machine which is constructed and arranged to perform the bending and flattening operations efficiently, and the construction of the machine is such that the investment cost thereof is relatively small with relation to the amount of work that the machine is capable of performing. In addition, a mechanic may readily learn to operate and handle the machine efficiently in a very short time.

Principal objects of the invention, therefore, are to provide:

A tube bending and flattening machine;

A tube bending and flattening machine which is constructed and arranged to bend tubing to form spaced runs and to flatten such runs.

Other and further objects of the invention will be apparent from the following description and claims and will be understood by reference to the accompanying drawings, of which there are five sheets, which, by way of illustration, show a preferred embodiment and the principles thereof and what we now consider to be the best mode in which we have contemplated applying those principles. Other embodiments of the invention embodying the same or equivalent principles may be used and structural changes may be made as desired by those skilled in the art without departing from the present invention and the purview of the claims. We also contemplate that of the several different features of our invention, certain ones thereof may be advantageously employed in some applications separate and apart from the remainder of the features.

In the drawings:

Fig. 1 is a side elevational view of part of a machine embodying the invention;

Fig. 2 is a plan view thereof with parts broken away and others shown in section;

Fig. 3 is a fragmentary plan view of part of

2
the apparatus shown in Fig. 2 but in another position thereof;

Fig. 4 is an enlarged view taken generally along the staggered line 4—4 of Fig. 1;

Fig. 5 is a fragmentary enlarged view of part of the apparatus shown in Fig. 4 but in a position thereof corresponding with that shown in Fig. 3;

Fig. 6 is an enlarged fragmentary sectional view taken generally along the line 6—6 of Fig. 1;

Fig. 7 is a perspective view of part of the control mechanism for the apparatus;

Fig. 8 is a plan view of a length of tubing after the same has been bent and flattened by the machine;

Fig. 9 is a horizontal sectional view taken generally along the line 9—9 of Fig. 1;

Fig. 10 is an enlarged sectional view taken along the line 10—10 of Fig. 9; and

Fig. 11 is a fragmentary sectional view taken along the line 11—11 of Fig. 1.

As illustrated in the embodiment of the invention selected for purposes of illustration, a machine for bending and flattening tubing comprises a supporting stand or table 10, tube bending means 12 (Fig. 9), tube flattening means 14 (Figs. 4 and 5), a vise 16 (Fig. 9) for holding the tubing while the bending and flattening operations are being carried on, suitable power operated means for actuating the foregoing, and a tube feeding means 18. The machine illustrated is particularly adapted for bending and flattening small diameter copper or copper-coated steel tubing which is useful in making heat exchangers, such as condensers, for use in refrigerating systems.

A length of such tubing 20 is shown in Fig. 9 extending through the tube feeding means 18, past a stationary jaw or clamp member 22 of the vise 16, and between the mandrel 24 and the ironing shoe 26 of the tube bending means 12. There is also illustrated in Fig. 9 in dotted lines a length of tubing which has been partially bent into the form of a serpentine coil positioned at A to have another bending operation performed thereon and positioned at B after such bending operation has been performed.

The vise 16 includes the stationary clamp member or jaw 22 and the movable jaw or clamp member 28. The member 22 has one side 30 thereof grooved as shown in Figs. 5 and 9, and the slideable jaw 28 has its face grooved so as to accommodate the tube 20 therebetween without crushing or damaging the same and so that when the jaw 28 is in the position relative to the mem-

ber 22 as shown in Figs. 4 and 9, the tube 20 will be clamped therebetween.

The slideable jaw 28 is mounted for movement toward and away from the member 22 by means of pins 32 which extend through slots in the member 28, the pins 32 being mounted on the surface on which the member 28 is slideable. Springs 34 bias the jaw 28 away from the member 22, while a cam 36 pivoted on a pin 38 has its end 40 engageable with the rear face of the jaw 28 for biasing and holding the jaw 28 against the member 22 for gripping the tube therebetween.

The cam 36 is in the form of a lever, the other end of which is pivotally connected to the reciprocating arm 42 of the air cylinder 44 for operating the vise. The air cylinder 44 includes the air operated piston (not shown) which is connected to the arm 42 so as to position the cam lever 36 in either of the positions illustrated in Fig. 9, the dotted line position being the released position of the vise.

The tube bending means comprises the stationary mandrel 24 and the ironing shoe 26. The mandrel 24 as illustrated is formed on the end of the member 22 and comprises a curved surface having a tube groove 50 therein defining the curve on which the tubing is to be bent. The ironing shoe 26 is slidably mounted on a rotary disc 52 having an arm 54 projecting therefrom.

A guide 56 is fixed to the disc 52 and together therewith forms a slideable support for the shoe 26. The guide 56 may have rollers 60 on which the shoe 26 may roll so as to reduce the friction between the shoe 26 and the guide 56. The shoe 26 has a tube groove therein and, as shown in Fig. 9, is arranged tangent to the mandrel 24 with the tube groove in the shoe 26 aligned with that of the mandrel 24 so as to permit the tubing 20 to extend therebetween.

The disc 52 is rotatable about the axis of curvature of the tube groove 50 in the mandrel 24, and when this occurs the disc 52 with the guide 56 and the shoe 26 will turn in a counterclockwise direction (Fig. 9) so as to bend the tubing 20 around the mandrel 24. During this movement the shoe 26 through the groove in which the tubing 20 extends, will bend the tubing around the groove 50 in the mandrel, the device being constructed and arranged so as to produce a bend in the tubing of one hundred eighty degrees.

In Fig. 9 a length of tubing 20 is shown in full lines projecting to the right of the mandrel 24 and the shoe 26. The first bending operation will form one bend in the tubing so that the tubing will then have two generally parallel runs separated by a bend. The coil indicated at A in dotted lines shows a partially bent length of tubing with three bends 70, 72 and 74 therein separating the parallel runs 76, 78, 80 and 82 thereof and positioned relative to the mandrel 24 for another bending operation to form another bend, while the coil indicated in dotted lines at B indicates the position of the coil after the additional bend 84 has been made therein.

After each bending operation the run of tubing ahead of the bend just made is positioned against the face 86 of the member 22; for example, after the bend 84 is made the run 82 ahead thereof is positioned against the face 86. The face 86 of the member 22 forms a jaw of the tube flattening means 14. The tube bending means thus positions the runs of tubing in position to be flattened by the jaws of the flattening means, as will be explained more fully hereinafter. After the bending operation the rotary parts of the

tube bending means including the shoe 26, the guide 56, and the arm 54 are returned to the position as illustrated in full lines in Fig. 9.

The arm 54 forms a support for the tubing during the bending operation. While the device is constructed and arranged so that the flattening operation is performed on each run ahead of the bend as soon as such bend is completed, the construction and operation of the flattening mechanism will be described hereinafter.

After each bending operation and flattening operation the vise 16 is released, as will be described hereinafter, and the feeding means 18 is actuated to advance the tubing 20 a distance equal to the distance between successive bends in the tubing. When this is done the runs will be positioned (looking at Fig. 9) above the line along which the tubing 20 is fed—that is, a line passing through the axis of the tube groove formed between the face 30 of the member 22 and the shoe 26 in the full line position illustrated in Fig. 9.

Thereafter, after the tubing has been advanced to the right as just described, the portion of the tubing which has been bent in the form of a coil will have to be swung about the longitudinal axis of the length of tubing just described so as to position the coiled portion of the tubing below such line and in position for the next bending operation.

A plan view of the partially bent piece of tubing is illustrated in Fig. 8. The number of bends and the distance therebetween may be as desired.

The disc 52 is keyed to rotate with a rotary head 90 on a shaft 92, the shaft being journaled in bearings 94 and 96 for rotation about its axis. A gear 98 is suitably fixed to the shaft 92, and the teeth of the gear 98 are arranged to mesh with the teeth of a reciprocable rack 100. The rack 100 is connected to a reciprocating member attached to the reciprocating piston of an air cylinder 104 whereby power may be supplied to the rack 100, the gear 98 and the tube bending means for operating the same. The air cylinder 104 is suitably connected to a source of air under pressure under the control of a valve whereby air may be supplied to the opposite ends of such air cylinder for actuating the piston thereof and the parts to which the piston is operatively connected.

The tube feeding means as illustrated comprises a handle 110 on one end of a slideable bar 112 having an arm 114 and a link 116 forming a connection with a lever 118 intermediate the ends thereof. The lever 118 is pivoted at 120 and has a slot 122 in the other end thereof into which a pin 124 (see Fig. 10) extends. The pin 124 projects downwardly from a block 126 which is slidably mounted on a guide rod 128. A wedge arm 130 is pivoted by means of a pin 132 to the block 126 and a torsion spring 134 biases the arm 130 in a counterclockwise direction about its pivot (Fig. 9). The block 126 and wedge arm 130 have abutting faces, each of which is grooved, as illustrated in Fig. 10, to form a groove through which the tubing 20 extends.

The construction of the feeding means is such that, looking at Fig. 9, the tubing 20 may be pulled or pushed to the right through the groove thereof formed between the wedge arm 130 and the block 126, while movement of the block 126 to the right by means of operation of the handle 110 will cause the arm 130 to wedge the tubing in the groove thereof against the block 126 and move the tubing 20 to the right in order to feed the same forward.

The feeding means 18 comprise a unidirectional feeding mechanism so that when the block 126 and wedge arm 130 are moved to the left, their grip on the tube 20 will automatically free itself and permit the tube 20 to remain in the position in which it is fed while permitting the feeding mechanism to be retracted for another feeding operation. Suitable stop means may be provided so as to accurately determine the proper distance for feeding the tube 20 forward for each bending operation. Obviously, the feeding means are actuated when the vise 16 is released when the tube bending means 12 are in the full line position as shown in Fig. 9.

The face 86 of the member 22 forms a stationary jaw of the tube flattening means which, as more clearly illustrated in Figs. 2, 3, 4 and 5, includes a movable jaw 140 carried on a shoe 142 pivoted at 144 to arms of a block 146. Springs 148 are provided for retracting the movable jaw 140 to the position illustrated in Fig. 5. Cams or wedges 150 are engageable with rollers 152 carried by links 154 pivoted on pins 156 for actuating the tube flattening means, that is, for closing the jaws thereof to the position as shown in Figs. 2 and 4. The pins 156 are carried on arms 158 on the shoe 142.

Fig. 2 shows the position of the cams 150 with the jaws of the tube flattening means closed, while Fig. 3 shows the position of the cams 150 with the jaws of the tube flattening means open. The cams 150 are connected to a rod 160 to be reciprocated thereby, the rod 160 being connected to the piston of an air cylinder 162, to the opposite ends of which air under pressure is supplied for shifting the cams 150 between the two positions as illustrated in Figs. 2 and 3. The cams 150 are backed up by rollers 164 suitably mounted on the block 146 so that pressure may be applied to the rollers 152 and the arms 158 of the shoe 142 for actuating the tube flattening means.

Air under pressure is supplied to the air cylinder 44 of the vise 16 under the control of a valve 166 which in turn is controlled by operating lever 168, the valve 166 with the control lever 168 in the position indicated in Fig. 1 being open, whereby the air cylinder 44 is holding the vise 16 closed. Movement of the control lever 168 ninety degrees in a clockwise direction will shut off the supply of fluid under pressure through the line 170 from the valve 166 to the air cylinder 44 for the vise 16 and vent the cylinder 44. The cylinder 44 may include a retracting spring (not shown) which automatically retracts the piston of the air cylinder for opening the vise 16 when the supply of air under pressure to the cylinder 44 is cut off by operation of valve 166. However, the vise 16 is not released until after a tube bending and a tube flattening operation have been performed.

Air under pressure is supplied to one end of the cylinder 104 through conduit 172 and to the other end of the cylinder 104 through conduit 173 under the control of a valve 174. The valve 174 has a control lever 176 therefor which upon being pushed downwardly will open the valve to permit air under pressure to be supplied through the conduit 173 to one end of the cylinder 104 in order to actuate the piston thereof to move the rack 100 to the right in order to actuate the tube bending means 12.

The valve 174 includes a valve operating shaft 175 having a ratchet wheel 177 fixed thereto. The lever 176 is pivoted on the shaft 175 and is provided with a spring pressed pawl 179 which is arranged to engage the teeth of the ratchet 177

so that when the lever 176 is pushed downwardly (clockwise about the axis of the shaft 175), the valve shaft 175 will be turned clockwise and shift the valve so as to supply air under pressure to the conduit 173. The valve 174 is suitably connected to a source of air under pressure and is of a type which is adapted selectively to connect such source of air under pressure to the conduits 172 and 173. The valve 174 includes a suitable return spring (not shown) for the lever 176 so as to normally position it as illustrated after it is operated as just described.

The rack 100 is provided with a laterally extending arm 180 to which trip lever 181 is pivoted at 183, and trip lever 185 is pivoted at 187. A spring 189 connected to the trip lever 181 and the arm 180 and a pin 191 on the arm 180 determine the normal position of the trip lever 181, while a spring 193 connected to an arm on the trip lever 185 and a pin 195 on the arm 180 determine the normal position of the trip lever 185. The arm 180 is arranged to move with the rack 100 so that near the end of the power stroke of the rack 100, the trigger 199 formed by one end of the trip lever 185 will engage a lever 201 and move it and the parts to which it is connected to the right.

An arm 203 pivoted on the shaft 175 is provided with a spring pressed pawl 205 which is arranged to engage the teeth of the ratchet wheel 177 for actuating the valve. The lower end of the arm 203 has a pin and slot connection 207 with a member 209 fixed to an axially slidable shaft 211. The shaft 211 is slidable in guides 213. A collar 215 fixed to the shaft 211 is biased by spring 217 which is confined between the collar 215 and one of the guides 213 for normally positioning the arm 203 in the position shown in Fig. 1.

The lever 201 is carried on an arm 219 which is fixed to one end of the shaft 211. A pin 221 on the arm 219 and a spring 223 connected to the lever 201 and the arm 219 normally position the lever 201 as shown in Fig. 11. As the rack 100 moves to the right, the trigger 199 will engage the lever 201 and through the mechanism just described swing the arm 203 in a counterclockwise direction about the shaft 175 so that the pawl 205 will engage with the next tooth to the right (Fig. 1) on the wheel 177.

As the tube bending mechanism completes the bending operation, the arm 225 on the trip lever 181 will engage the adjustable stop 227 which causes the trip lever 181 to swing in a clockwise direction (Fig. 11) about its pivot 183, thereby releasing the trip lever 185 and permitting the spring 217 to return the arm 203 and the parts connected to move therewith to the position illustrated in Fig. 1. When the trip lever 185 is released, it is free to swing in a clockwise direction about its pivot 187 under the influence of the lever 201.

The action of the spring 217 in moving the arm 203 in a clockwise direction about the axis 65 of the shaft 175 will, through the engagement of the pawl 205 with the teeth of the ratchet wheel 177, turn the valve shaft 175 and the valve so as to shut off the supply of air to the conduit 173 and establish communication between the air supply 70 and the conduit 172.

The valve 174 also includes provisions for venting each side of the cylinder 104 when the air supply thereto is shut off. When the valve 174 establishes communication between the supply of air under pressure and the conduit 172, air will

be supplied to one side of the cylinder 104 so as to effect the return or retracted stroke of the tube bending means, thus returning the tube bending means to its starting position as shown in full lines in Fig. 9.

After the lever 201 moves to the left beyond the trigger 199, the springs 193 and 189 will return the trip levers 185 and 181 to their positions as illustrated on the arm 180. During the retractile movement of the rack 100, the lever 201 is free to swing so as to permit the trigger 199 to move to the left past the same, and thereafter the spring 223 will normally position the lever 201 as shown.

As the rack 100 moves to the right, an arm 190 (Figs. 1 and 7) pivoted on the rack moves to the right past pin 230. The pin 230 is carried on an arm 192 which is pivoted on the control shaft 231 of the valve 194. The valve 194 is essentially like the valve 174 and is connected to a source of fluid under pressure and is adapted upon step-by-step rotation of the shaft 231 to alternately supply such fluid to opposite ends of the cylinder 162 of the tube flattening means. In one position of the valve fluid under pressure will be supplied through the conduit 196 to effect the power stroke of the tube flattening means, while in another position of the valve air under pressure will be supplied to the opposite side of the cylinder 162 through the conduit 208 to effect the return stroke thereof and permit the springs 148 to open the jaws of the tube flattening means.

Like the valve 174, the valve 194 will vent each end of the cylinder 162 when the supply of air under pressure thereto is cut off. The valve shaft 231 has a ratchet wheel 232 fixed thereto, and the lever 192 is provided with a spring pressed pawl 234 which upon movement of the lever 192 in one direction about the axis of the shaft 231 will shift the valve 194 so as to establish communication between the supply of air under pressure and the air cylinder 162 through the conduit 196 so as to effect the power stroke of the air cylinder 162 of the tube flattening means.

Thus, upon the retractile stroke of the rack 100, the lever 190 will engage the pin 230 and through the arm 192, pawl 234, and ratchet wheel 232 turn the shaft 231 so as to supply air under pressure to the conduit 196 at the end of the return stroke of the tube bending means, as previously described. Supplying air to the cylinder 162 through the conduit 196 will actuate the tube flattening means to flatten the length of tubing which has just been positioned by the tube bending means. At this time the tube flattening means will be in the positions illustrated in Figs. 2 and 4.

After the tube flattening operation has been completed, the lever 168 is shifted ninety degrees clockwise so as to release the vise 16. A connection is provided between the lever 168 and the valve 194 for shifting the same so as to restore the tube flattening means to their starting position, that is, to the positions illustrated in Figs. 3 and 5. This connection comprises a link 236 pivotally connected at one end thereof to one end of the lever 168 and a pin and slot connection 238 between the other end of the link 236 and one arm 240 of a bell crank. The bell crank includes a shaft 242 pivoted in a bracket 244 and an arm 200 fixed to shaft 242. The arm 200 is engageable with a rod 202 bolted to an arm 204 and projecting laterally therefrom. The arm 204 is pivoted on the shaft 231 and is provided with a spring pressed pawl 246 which is engageable with the teeth of the ratchet wheel 232 at the end of

the shifting movement of the lever 168 just described so as to turn the valve shaft 231 so as to actuate the valve 194 to shut off the communication of air under pressure to the cylinder 162 through the conduit 196 and to vent the side of the cylinder 162 to which the conduit 196 is connected, and at the same time to establish communication between the supply of air under pressure and the conduit 208 so that air under pressure will be supplied to the other end of the cylinder 162 in order to retract the piston thereof and shift the cams 150 from the position shown in Fig. 2 to that shown in Fig. 3, thereby restoring the tube flattening means to its starting position and opening the jaws thereof.

A spring 250 acting on the lever 192 normally positions it as illustrated. A spring (not shown) normally positions the valve lever 204 in the position as illustrated. The valve levers 192 and 204 act independently on the ratchet wheel 232. The lever 204 is manually actuated or controlled, while the lever 192 is controlled by the return movement of the rack 100.

The valves 166, 174 and 194 are standard forms of air control valves which are available for controlling the supply of air under pressure to work cylinders, the valve 166 being a single valve while the valves 174 and 194 are double valves, that is, valves which are adapted to control the supply of air under pressure to opposite ends of the cylinder alternately and to vent the air pressure on one side while air under pressure is being supplied to the other side of the cylinder. Since the details of these valves form no part of the invention, no further illustration or explanation of the construction thereof is considered to be necessary to an understanding of the invention claimed.

Thus a length of tubing 20 to be bent and flattened is inserted into the machine from the left-hand end (Fig. 9) through the feeding mechanism 18 so that the forward end of the tubing will be positioned approximately as indicated in Fig. 9 in position to be acted upon by the tube bending means 12. The lever 168 of valve 166 is then operated to supply air to the cylinder 44 in order to effect the closure of the vise 16. The lever 176 of the valve 174 is then depressed which effects the supply of air to one end of the cylinder 104 through the pipe 173 so as to effect a tube bending operation of the tube bending means 12. During the tube bending operation the rack 100 moves to the right (Fig. 1) so as to bend the tubing around the mandrel 24. At the end of the movement to the right of the rack 100 the valve tripping mechanism associated with the arm 203 resets the valve 174 so as to effect a return movement of the rack 100 and the restoration of the tube bending means to the full line position shown in Fig. 9. At the end of the retracting stroke of the rack 100 the arm 190 thereon will operate the valve 194 which controls the supply of air to the cylinder 162 to supply air to the cylinder 162 so as to effect a tube flattening operation of the tube flattening means 14 on the run of the tubing 20 which has been positioned by the tube bending means 12 to be acted on by the jaw 140 of the tube flattening means 14. After the tube flattening operation has been completed, the lever 168 is shifted 90° clockwise so as to release the vise 16 and coincident with this the connection between the lever 168 and the valve 194 will shift the latter so as to effect the return stroke of the piston of the cylinder 162 and restore the tube flattening means 14 to its starting position. Thereafter the tube feeding

means may be actuated to advance the tubing sufficiently so that another run of tubing may be formed, but before the cycle of operations is again repeated the end of the tubing 20 which has the bend thereon must be flopped over, as previously described, so that the next bending operation of the tubing will be to form a bend opposite to that previously formed.

While we have illustrated and described a preferred embodiment of our invention, it is understood that this is capable of modification and we therefore do not wish to be limited to the precise details set forth but desire to avail ourselves of such changes and alterations as fall within the purview of the claims.

We claim:

1. In a machine for bending and flattening tubing to form a serpentine coil, tube bending means constructed and arranged to bend a length of tubing to form spaced runs therein, tube flattening means constructed and arranged to flatten such runs of said tubing, said means being constructed and arranged relative to each other so that said tube bending means will position a run of said tubing in position to be flattened by said tube flattening means.

2. In a machine for bending and flattening tubing to form a serpentine coil, tube bending means, tube flattening means, a source of power connected to said means for operating the same, said tube bending means being constructed and arranged to bend a length of tubing to form spaced runs therein, said tube flattening means being constructed and arranged to flatten such runs of said tubing between the bends therein, and means operable for gripping a portion of the length of tubing other than that being bent or flattened during the bending and flattening operations.

3. A tube bending and flattening machine according to claim 2 wherein said source of power is connected to said bending and flattening means in such a manner so as to successively actuate said means.

4. In a machine for bending and flattening tubing to form a serpentine coil having a series of alternate runs and bends all lying in the same plane, tube bending means, tube flattening means, a source of power connected to said means for operating the same, said tube bending means being constructed and arranged to bend a length of tubing to form spaced runs therein and bends between successive runs, said tube flattening means being constructed and arranged to flatten only the runs of said tubing between the bends thereof, and mechanism intermittently operable for feeding said tubing to said means between each tube bending operation.

5. A machine according to claim 4 wherein means are provided for gripping a portion of the length of tubing other than that being bent or flattened only during the bending and flattening operations.

6. A machine according to claim 2 wherein a stationary member is formed to provide a part of each of said means.

7. In a machine for bending and flattening tubing to form a serpentine coil, tube bending means, tube flattening means, and a source of power connected to said means for operating the same, said tube bending means being constructed and arranged to bend a length of tubing to form spaced runs therein, said tube flattening means being constructed and arranged to flatten each of said runs of said tubing ahead of a bend there-

in, said source of power being constructed and arranged so as to actuate said bending means and said flattening means in the order named.

5 8. In a machine for bending and flattening tubing to form a serpentine coil having a series of alternate runs and bends all lying in the same plane, tube bending means constructed and arranged to bend a length of tubing to form spaced runs therein, tube flattening means constructed and arranged to flatten only the runs of said tubing, and unidirectional mechanism operable for intermittently feeding tubing to said means and constructed and arranged to permit the tubing to be advanced relative to said means when 15 said means and said mechanism are inoperable.

9. A tube bending and flattening machine according to claim 8 wherein said means are constructed and arranged relative to each other so as to be operable one after the other and where- 20 in one of said means positions said tubing to be acted on by the other of said means.

10. In a machine for bending and flattening tubing, a vise engageable with a part of a length of tubing for holding the same, a stationary member forming a part of said vise and having a mandrel at one end thereof around which the tubing may be bent and alongside of which mandrel tubing to be bent is fed, an ironing shoe positioned adjacent said mandrel and so that tubing 30 may extend between said shoe and mandrel, said shoe being cooperable with said mandrel by movement relative thereto for bending the tubing around said mandrel, a tube flattening means engageable with a portion of said tubing ahead 35 of the bent portion thereof for flattening said tubing to form a hollow flat portion, said stationary member forming a part of said tube flattening means, power operated means connected to said ironing shoe for moving the same to bend the tubing around said mandrel and power operated means connected to said flattening means for actuating the same to flatten a part of the tubing ahead of said mandrel.

11. In a machine for bending and flattening tubing, a vise engageable with a part of a length of tubing for holding the same, a mandrel around which the tubing may be bent and alongside of which mandrel tubing to be bent is fed, an ironing shoe positioned adjacent said mandrel and so that tubing may extend between said shoe and mandrel, said shoe being cooperable with said mandrel by movement relative thereto for bending the tubing around said mandrel, a tube flattening means engageable with a portion of said tubing ahead of the bent portion thereof for flattening said tubing to form a hollow flat portion, power operated means connected to said ironing shoe for moving the same to bend the tubing around said mandrel and power operated means connected to said flattening means for actuating the same to flatten a part of the tubing ahead of said mandrel.

12. In a machine for bending and flattening tubing, a mandrel around which tubing may be bent and alongside of which mandrel a length of tubing to be bent is fed, an ironing shoe positioned adjacent said mandrel and so that tubing may extend between said shoe and mandrel, said shoe being cooperable with said mandrel by movement relative thereto for bending the tubing around said mandrel, a tube flattening means engageable with a portion of said tubing for flattening such portion of said tubing, power operated means connected to said ironing shoe for moving the same to bend the tubing around said

11

mandrel and power operated means connected to said flattening means for actuating the same to flatten a part of the tubing, said mandrel and ironing shoe being arranged relative to said tube flattening means so as to position such portion of said tubing at the ends of a bending operation in position to be flattened by said tube flattening means.

13. A machine for bending and flattening tubing according to claim 12 wherein said tube flattening means comprises a pair of jaws between which such portion of said length of tubing is positioned so as to be flattened upon the closing of the jaws.

JAMES R. HAYWARD. 15
